(57) **CLAIM**

The ornamental design for a loudspeaker, as shown and described.

DESCRIPTION

FIG. 1 is a closed state perspective view of the loudspeaker, showing my new design.

FIG. 2 is an open state perspective view of a loudspeaker.

FIG. 3 is a front view of the loudspeaker.

FIG. 4 is a rear view of the loudspeaker.

FIG. 5 is a left side view of the loudspeaker.

FIG. 6 is a right side view of the loudspeaker.

FIG. 7 is a top view of the loudspeaker; and,

FIG. 8 is a bottom view of the loudspeaker.

The broken lines depict portions of the loudspeaker that form no part of the claimed design.
